(57) CLAIM

The ornamental design for a fitness weight destabilizer, as shown and described.

DESCRIPTION

FIG. 1 is a perspective view of the design;

FIG. 2 is a right end view thereof, the left end view being a mirror image thereof;

FIG. 3 is a front view thereof, the rear view being a mirror image thereof;

FIG. 4 is a top view thereof; and,

FIG. 5 is a bottom view thereof.

The broken line showing of portions of the fitness weight destabilizer depicts environment and forms no part of the claim.
